UNITED STATES PATENT OFFICE.

EDWARD C. GAINES, OF MONTREAL, QUEBEC, CANADA.

DOOR OPENER.

1,405,404.

Specification of Letters Patent. Patented Feb. 7, 1922.

Application filed September 9, 1919. Serial No. 322,766.

To all whom it may concern:

Be it known that I, EDWARD C. GAINES, a citizen of the United States, residing in the city of Montreal, Province of Quebec, Dominion of Canada, mechanical engineer, have invented certain new and useful Improvements in Door Openers, for which the following is a full, clear, and exact description thereof.

10 My invention has reference to power mechanism for opening doors. Heretofore it has been proposed to open doors of coke ovens and grain and coal doors of box cars, etc. by mechanism of a cumbersome and more or less complicated nature and slow in operation. To simplify the construction and obtain a direct and continuous unitary operation is the object of my invention and to this end the invention comprises a pair of 15 power operated arms adapted to act upon the inner grain door of a car, with the object of forcing this grain door off of its nails into the car, and upwardly moving it in a curved path to a position affording sufficient 20 clearance to permit the lading to flow freely out through the door opening and at the same time accommodate any auxiliary unloading implements that may be necessary 25 to use within the car to assist in deflecting the material and the door opening. This 30 function is performed in a single continuous operation. The majority of doors opened in this way will not be broken and can be used again saving the expense of new doors.

35 While this specification describes the application of my invention particularly in connection with the opening of grain doors of railway box cars loaded with grain, it is equally applicable to the opening of the inner door of box cars loaded with coal, sand or any material in bulk.

For full comprehension of my invention reference must be had to the accompanying drawings in which similar reference characters indicate the same parts, and wherein:

Figure 1 is a side elevation of my improved power mechanism for opening grain doors with the door dislodging arms illustrated in full lines in position to act upon the grain door and in two dotted positions illustrating the successive continuous movements from full back position to its position after having swung the grain door through the grain and to a point within the car near the top thereof;

Figure 2 is a detail view partly in elevation and partly in section drawn to a larger scale and illustrating a part of the means by which the arms are relatively adjusted laterally;

Figure 3 is a plan view of the embodiment of my invention for use in the unloading of grain cars by the forcing of the grain door inwardly;

Figure 4 is an elevation of the right hand side of the power mechanism as viewed in Figure 1;

Figure 5 is a detail vertical sectional view taken on line 5—5 Figure 6;

Figure 6 is a front elevation partly in section of the bearing face of one of the arms; and

Figure 7 is a horizontal sectional view taken on line 7—7 Figure 5.

A suitable frame for supporting my invention in position to displace grain doors consists of posts 10, cross-braces 12 and parallel fore and aft beams 13 serving as a support for the mechanism of the arms and the arms themselves; while a bin 14 is adapted to receive grain from the grain car indicated at 15 and supported on a track 16 over the bin.

The pair of door displacing arms correspond in all respects and each consists of a toothed quadrantal part *b*, with tapered extension *c* reinforced with flanges *d*. The end of the tapered arm has a forwardly extending bearing member *e* carrying a box-like guiding member *f*, the face of which is adapted to bear upon the grain door.

This guiding member has slidably mounted therein parallel to its bearing face a bar 80 having fixed thereon a plurality of spikes.

These spikes are adapted to bite into the grain door when the latter is forced open. The door when being forced open moves substantially transversely to the car until the nails are free and as the arms swing in a curved path there is a slight relative movement between the latter and the door during the initial opening movement.

This relative movement is taken up by a helical spring 81 located at the lower end of the bar and is adapted to yieldingly maintain the latter in 105 its uppermost position. The guiding member also slidably carries in telescopic relation therewith a freely movable bearing member *g*, the lower end of which is sheared off as at 95 *g'* and has pivotally mounted therein a 110

trundle roller *i*. This roller is adapted to rest upon the platform of the door opening when in door opening position and to engage a fixed cam to be hereinafter described when swung away from the car. A shank *j* extends upwardly into the box-like member and carries a pair of rollers *m* the free ends of the pin *o* upon which these rollers are mounted protruding slidably through a pair 10 of bayonet slots *p* in the sides of the box, a bearing shoe *g*¹ on the rear side of member *g* transmits the thrust upon this member when displacing the door to the lower end of the arm. The relative dimensions of these 15 slots *p* and the positions thereof and the roller *m* and pin *o* are such that the extensible bearing member *g* may be readily pushed up into the box guide and the pin *o* be made to rest on the shoulder *q* of the 20 bayonet slot, thus supporting this device in its uppermost position in the guide and with its bearing face *g*' projecting beyond the bearing face of *f*. This position of the parts is accommodated by an angular recess *r* 25 adapted to engage the lower edge of the bearing face *f*¹. As will be explained in connection with the operation this extensible bearing device fulcrums on the roller *m*.

In order to return this extensible bearing 30 device to its position within the guide a fixed cam *s* is yieldingly mounted within the frame of the structure and disposed in position relatively to the path of the arm to be engaged by the roller *i* when the arm is 35 swung to full back position. A pair of these cams are required for a pair of arms. Of course this extensible bearing member may be returned to its position within the guide by hand, if desired, without departing from 40 the spirit of my invention.

These arms are mounted on a pair of aligned shafts 2 to which they are fulcrumed between a pair of collars 20 in order that they may be moved with the shafts for the 45 purpose of adjusting the width of the space between the arms to accommodate different widths of grain doors. This adjustment is effected by a sleeve-nut 4 engaging right and left hand screws 5 and 6 respectively secured 50 to the shafts 2, the sleeve-nut having formed integrally therewith or fastened rigidly thereto a sheave 7, the rotation of which in one direction or the other moves the shafts 2 towards or away from each other and the 55 arms move laterally with them, thereby adjusting their respective positions. The operation of this adjusting sheave is effected by a rope or chain 25 looped around the sheave and over a pair of pulleys or sheaves 60 26 bent down and around the pulley or sheave 27 carried in a forked clevis 28 mounted on the machine frame in order that the slack of the rope or chain may be automatically taken out, and if necessary tension 65 imparted to the rope or chain by a helical

spring 29 bearing between a collar 30 on a link-bar 31 connected to the clevis 28 and extending through the frame; the spring bearing between the washer and the frame and exerting a downward pull on the clevis. 70

In this embodiment of my invention the arms are swung by a quadrantal toothed rack 50 formed integrally with the quadrantal part of the arm or fastened rigidly thereto as may be desired. The racks of the two 75 arms are engaged and operated by a pair of elongated spur-gears 51 driven by a shaft 52 upon which is rigidly mounted a worm-wheel 53 driven in turn by a worm 54 on the shaft of an electro-motor 55. 80

The movement of the ropes or chains 25 by hand takes care of the lateral adjustment of the arms to correspond properly with the width of the door opening, while the extensible member *g* takes care of different heights of car floors. 85

Operation.

A car to be unloaded is run onto the siding or car unloader of which the rails 16 form 90 a part, and when blocked in position with its door over the hopper or chute and consequently in position between the arms, the latter are adjusted laterally, if necessary, to enter the door opening. The motor is then 95 started, thereby swinging the arms to position shown at B in Figure 1 or in any desired position within the car, the particular machine illustrated permitting the door to be swung to a point near the top of the interior of the car but with sufficient clearance to avoid striking the top of cars of minimum height. When the car has been emptied the arms are swung back to a position C (Fig. 1), the door striking against the door posts 100 and being pulled off of the spikes in the arms, drops on the floor of the car. 105

As the arms swing in performing their function the first part to come in contact with the grain door is the extensible member *g* of the bearing face which is arrested by the door as the arm continues its movement, thus releasing the pin *p* from the shoulder *q* and permitting the member *g* to fall. As the bearing face will be inside of 110 the upper edge of the car floor when this happens, the member *g* will fall upon this floor and the bearing face will automatically be extended accordingly. As the arms continue forcing the door through the lading 115 the extending bearing face will insure a support for the full depth. 120

It will be observed that there is no mechanical necessity to stall or hold the grain door between the beginning and end of its movement which is a continuous unitary one, from its nailed position to its highest position desired in the interior of the car. 125

What I claim is as follows:

1. A door opening mechanism comprising 130

- a pair of arms fulcrumed to swing transversely to the plane of the door, the centre of gravity of each arm being located below its point of fulcrum, and means whereby 5 the arms are swung.
2. A door opening mechanism comprising a pair of arms fulcrumed to swing transversely to the plane of the door, the centre of gravity of each arm being located below its point of fulcrum, and power 10 means whereby the arms are swung.
3. A door opening mechanism comprising a pair of arms fulcrumed to swing transversely to the plane of the door, the centre of gravity of each arm being located below its point of fulcrum, and power 15 means whereby the arms are swung, said power means being constructed and arranged to operate upon the upper portion of the arm.
4. A combination with a support frame having a hopper or chute in its substructure and power mechanism on its superstructure, and a pair of arms adapted to swing in parallel planes, means for pivotally connecting the arms to the superstructure, means for operatively connecting the power mechanism to the upper portion of the arms, and the lower end having a bearing face in a position in advance of the general forward line of the arms. 20
5. A door opening mechanism comprising a pair of arms pivotally mounted to swing transversely to the plane of the door, means whereby the arms are swung and telescopic 25 means upon each arm constructed and arranged to automatically adjust the length of bearing face required.
6. A door opening mechanism comprising a pair of arms pivotally mounted to swing 30 transversely to the plane of the door, the axis upon which the arms swing being located above the bottom of the door, and means whereby the arms are swung; the bearing face of each arm having a guide on 35 which is slidably mounted a member adapted to vary the length of the said bearing face, and adapted to limit the vertical movement of the said member therein, means for displaceably supporting the said member 40 and means whereby a displacement of the member causes the same fall to the extent of the guide.
7. A combination with a support frame having a hopper or chute in its substructure 45 and power mechanism on its superstructure, and a pair of arms adapted to swing in parallel planes, means pivotally connecting the arms to the superstructure, means operatively connecting the power mechanism to the upper end of the arms, and the lower end having a bearing face in a position in advance of the general forward line of the arms, such operative connection consists of a pair of quadrantal gears carried 50 rigidly by the said upper portion of the arms, motor driven shaft, elongated gears, mounted upon the shaft to rotate therewith and operatively engage the quadrantal gears.
8. A door opening mechanism comprising a pair of arms fulcrumed to swing transversely to the plane of the door, the centre of gravity of each arm being located below its point of fulcrum, means whereby the arms are swung and means for adjusting the arms to and from one another for the purpose of adjustment to accommodate different widths of door openings. 70
9. A door opening mechanism comprising a pair of arms pivotally mounted to swing transversely to the plane of the door, the axis upon which the arms swing being located above the bottom of the door, and means whereby the arms are swung, and means for adjusting the arms to and from one another for the purpose of adjustment to accommodate different widths of door openings, such adjusting means consisting of a pair of aligned shafts serving as the pivots for the arms and means for relatively adjusting the shafts axially. 80
10. A door opening mechanism comprising a pair of arms pivotally mounted to swing transversely to the plane of the door, the axis upon which the arms swing being located above the bottom of the door, and means whereby the arms are swung, and means for adjusting the arms to and from one another for the purpose of accommodating different widths of door openings, such adjusting means consisting of a pair of aligned shafts serving as the pivots for the arms and means for relatively adjusting the shafts axially. 85
11. A mechanism for opening doors of box cars and the like nailed in position closing the car door opening said mechanism including an oscillatory member fulcrumed from a fixed point adjacent the door opening and located near the top of said member and constructed and arranged to be swung through the latter and means slidably mounted upon said member and constructed and arranged to permit of movement of the door in a substantially horizontal direction until the nails are free. 90
12. A mechanism for opening doors of box cars and the like nailed in position closing the car door opening, said mechanism including an oscillatory member fulcrumed from a fixed point adjacent the door opening and constructed and arranged to be swung through the latter, a bar slidably mounted upon said member and constructed and arranged to permit of movement of the door 95
- 130

in a substantially horizontal direction until the nails are free, a plurality of devices rigidly mounted upon said bar and adapted to bite into the door to be opened, and a spring 5 yieldingly resisting movement of the bar relatively to said member.

13. A door opening mechanism including an oscillatory member fulcrumed to swing transversely to the plane of the door, said member having its centre of gravity located below its point of fulcrum.

14. The combination with a structure having an opening and a door closing said opening, of a mechanism for the purpose set forth including an oscillatory member fulcrumed from a point above the level of the top of the door and constructed and arranged to be swung through the door opening.

20 15. The combination with a box car having a door opening and a door closing said opening, of means constructed and arranged to remove the door to a position within the car and above the lading by one continuous 25 operation.

16. A door opening mechanism including an arm fulcrumed to swing transversely to the plane of the door to be opened, the lower end of said arm presenting a bearing face 30 adapted to engage the door and such lower end being of hollow form, a telescopic member located within the said lower end, means for displaceably maintaining said member in raised position within said end and projecting outwardly therefrom in advance of the bearing face whereby the telescopic member is adapted to engage the door in 35 advance of the bearing face and drop to a

position adjacent the lower edge of the door.

17. A door opening mechanism comprising a supporting structure, a pair of arms fulcrumed in said structure and adapted to swing transversely to the plane of the door, the centre of gravity of each arm being located below its point of fulcrum, and means whereby the arms are swung said means being located in a position clear of the door opening.

18. A car door opening mechanism comprising a supporting structure, a pair of arms fulcrumed in said structure and adapted to swing transversely to the plane of the door, the centre of gravity of each arm being located below its point of fulcrum, and power means whereby the arms are swung said means being located in a position clear of the door opening.

19. A door opening mechanism comprising a supporting structure, a pair of arms fulcrumed in said structure and adapted to swing transversely to the plane of the door, centre of gravity of each arm being located below its point of fulcrum, and power means whereby the arms are swung said power means being constructed and arranged to operate upon the upper portion of the arm and located in a position clear of the door opening.

In testimony whereof I have signed to this specification in the presence of two witnesses.

EDWARD C. GAINES.
